(57) **CLAIM**

I claim the ornamental design for a base for a barbecue grill, as shown and described.

DESCRIPTION

FIG. 1 is a top front perspective view of a base for a barbecue grill showing my new design;
FIG. 2 is a top plan view thereof;
FIG. 3 is a rear elevational view thereof;
FIG. 4 is a right side elevational view thereof;
FIG. 5 is a left side elevational view thereof;
FIG. 6 is a front elevational view thereof;
FIG. 7 is a bottom plan view thereof; and,
FIG. 8 is a perspective view thereof, the grill shown in broken lines forms no part of the claimed design.
